UNITED STATES PATENT OFFICE.

WILLIAM HARBISON SPEAR, OF BISMARCK, NORTH DAKOTA.

WHIFFLETREE-HOOK.

1,135,733.

Specification of Letters Patent. Patented Apr. 13, 1915.

Application filed July 25, 1914. Serial No. 853,218.

To all whom it may concern:

Be it known that I, WILLIAM HARBISON SPEAR, a citizen of the United States, residing at Bismarck, in the county of Burleigh 5 and State of North Dakota, have invented certain new and useful Improvements in Whiffletree-Hooks; and I do hereby declare the following to be a full, clear, and exact description of the invention, such as will 10 enable others skilled in the art to which it appertains to make and use the same.

This invention relates to new and useful improvements in whiffletree hooks, and has for its principal object to provide a device 15 which may be arranged to be secured to a whiffletree to form a securing means for the same.

Another object of the invention is to provide a safety whiffletree hook from which 20 the tug cannot become released accidentally.

A further object of the invention is to provide a device which may be easily and cheaply constructed so that the cost of production will be at a minimum.

With these and other objects in view, the 25 invention consists in the novel combination and arrangements of parts which will be fully set forth in the following specification and accompanying drawings, in which,

Figure 1 is a detail perspective view of a 30 connection for a whiffletree hook constructed in accordance with this invention, Fig. 2 is a longitudinal sectional view of the same illustrating it as it would appear when in use 35 on a whiffletree, Fig. 3 is a sectional view taken on line 3—3 of Fig. 2, Fig. 4 is a view of the blank of which the hook supporting body is formed.

Referring now to the drawings by characters of reference, the numeral 1 designates 40 the whiffletree to which the whiffletree hook, designated generally by the numeral 2, is secured. This whiffletree hook comprises the main body portion 3 having the side 45 members 4 formed integral therewith. These side members 4 are tapered as illustrated in the drawings and are provided at their wider ends with the connecting band 5 which coöperates with the remaining portions 50 of the whiffletree hook connection in forming a socket for the reception of the end of the whiffletree as illustrated in Fig. 2. Formed at the forward end of the socket thus formed are the longitudinal extensions 55 6 which are spaced from each other to form

the slots 7 in which the hook 8 is held on the pivot member 9. The rear walls of the members 6 are curved as at 10 in order to prevent the tug from becoming displaced should the same become slackened. In the 60 form illustrated in Figs. 1, 2, and 3, these members are formed contiguous with the side walls 4 of the socket and are provided with the rivet 11 which takes the place of the pivot pin 9 hereinbefore referred to. 65

It will be apparent from the foregoing that in use, the device is slipped over the end of a whiffletree as illustrated in the drawings and the bolt or screw 12 extended through the aperture formed in the wall 3. 70 It will thus be seen that the device will be firmly held in place and accidental movement thereof will be prevented. To attach the tug to the hook, the same is swung to the position illustrated in the dotted lines 75 in Fig. 2 and the links carried by the end of the tug passed thereover and the hook is permitted then to swing around as shown in full lines. It will thus be apparent that the links of the tug are prevented from being 80 unhitched without first swinging the hooks and manually releasing the tug.

While in the foregoing there has been shown and described the preferred embodiment of this invention, it is to be understood 85 that such changes may be made in the combination and arrangement of parts as will fall within the spirit and scope of the invention as defined in the appended claim.

What is claimed is:

A whiffletree hook holder formed of a single sheet of metal bent to form a body portion having a socket at one end, lateral spaced extensions at its opposite end, said lateral extensions being bent inwardly at 95 their point of connection with the body forming a pair of shoulders limiting the inward movement of said body on a whiffletree, a pivot pin extending transversely through the extensions adapted to hold a 100 hook thereon, and means for connecting the body portion on the whiffletree and preventing any outward movement of the same.

In testimony whereof I affix my signature in presence of two witnesses.

WILLIAM HARBISON SPEAR.
